UNITED STATES PATENT OFFICE.

LEE S. CHADWICK, OF SHAKER HEIGHTS, OHIO, ASSIGNOR TO THE CLEVELAND METAL PRODUCTS COMPANY, OF CLEVELAND, OHIO, A CORPORATION OF OHIO.

AUTOMATIC WICK STOP FOR OIL BURNERS.

Application filed March 5, 1921, Serial No. 449,842. Renewed June 6, 1923. Serial No. 565,746.

To all whom it may concern:

Be it known that I, LEE S. CHADWICK, a citizen of the United States, residing at Shaker Heights village, in the county of Cuyahoga and State of Ohio, have invented a certain new and useful Improvement in Automatic Wick Stops for Oil Burners, of which the following is a full, clear, and exact description, reference being had to the accompanying drawings.

My present invention, like those constituting the subjects matter of my former applications Serial Nos. 448,108 and 448,109, filed February 26, 1921, has to do with improvements in oil burners of the class employing wicks, and it relates more particularly to means for restricting the wick against being raised above a predetermined elevation.

The objects of the invention are to provide a thoroughly reliable and automatic wick stop which is positive in its action; not likely to get out of order; is durable; simple of construction and comparatively inexpensive of manufacture, and which, when incorporated in burners of the tubular type, is concealed from view.

To these ends my invention may be defined in general terms as consisting of a brake member adapted to directly engage the wick; a member adapted to be engaged by the top of the wick and displaced thereby as the wick is elevated; operative connections between said member and the brake; and means affording a limited movement of the wick after it is engaged by the brake. The essential point of difference of my present invention from the inventions disclosed in my aforesaid applications is that in the present case the stop device or brake member contacts with the wick, whereas, in the others, the stop mechanism co-acts with a part of the wick raising means to arrest the movement of the wick.

With reference to the accompanying drawing wherein like characters designate corresponding parts throughout the several views, Fig. 1 is a central vertical section through a burner incorporating one form of my invention; Fig. 2 is a sectional detail on the line 2-2 of Fig. 1; Fig. 3 is a view similar to Fig. 1 of a modification; while Fig. 4 is a sectional detail on the correspondingly numbered line of Fig. 3.

In general respects, the burners shown in

Figs. 1 and 3 are the same and are of the tubular type, the inner and outer wick tubes being designated 1 and 2, respectively, and being joined at their lower ends by an annular wall 3, thereby to enclose a space 4 wherein a wick 5 is adapted to be raised and lowered by means of a wick-raising spindle 6, having the usual star wheels or pinions 7 that mesh with a wick carrier 8 applied to the lower portion of the wick. The wick space 4 derives its supply of fuel from a pipe 10, whereon the burner is mounted, through a common form of connection between the pipe and burner (not shown). A flame spreader 12 is shown in dotted lines as supported in operative relation to the upper end of the wick. Inasmuch as the foregoing is a common and well-known construction, further and more detailed description thereof is deemed unnecessary.

In each modification, the inner wick tube 1 is provided with an oil tight casing 15, the interior whereof communicates with the wick space 4 through slots in the inner wick tube. The casings 15 accommodate the wick stop mechanism which I shall now describe.

In the form of the invention illustrated in Figs. 1 and 2, a lever 20 is journaled upon a pin 21 that is supported by and between the side walls of the casing 15, the lever 20 carrying a roller 22 at its upper end for engagement with the top of the wick, and a roller 24 at its lower end for engagement with the rear side of a brake member 25. The brake member is connected, through links 26, with a bar 27 to form a parallelogram, and the pins 28 through which the links 26 are connected to the bar 27 carry rollers 29 that traverse the inner vertical wall of the casing 15; thereby to restrict the assembly to a vertical course of movement.

In this form of the invention, when the wick is elevated and engages and displaces laterally the roller 22, it will swing the lever 20 in a direction to force the brake member 25 toward the wick and into engagement with a roughened or finely corrugated strip 30, which may be an extension of the wick carrier 8, and wherewith the wick is preferably provided to protect it against being mutilated by the brake member. As the wick continues to rise, it will carry with it the brake member and parts connected thereto until the upper roller 29 engages an adjustable stop 31 in the form of a screw 110

threaded through a member supported by the casing 15.

Upon the return of the parts to normal position, the movable assembly will come to rest (through the lower roller 29) on an abutment 32 carried by the casing 15. Should the weight of the brake member 25 be insufficient to dislodge it from the wick, a spring 33 may be included for this purpose which is shown as having one of its ends connected to the brake member and its other end anchored to the casing 15.

In order that the wick may be removed from the burner, as for the purpose of replacing it by a new wick, it is necessary to temporarily render inoperative the wick stop mechanism. I have shown as means for accomplishing this a cam lever 35 that is pivoted at 36 to the casing 15 and which has a part cooperating with the pivot pin 21 of the lever 20 where the pin projects through slots 37 in the casing for holding the pin in the forward end of the slot with the roller 22 of lever 20 in the path of the wick. The cam lever 35 is preferably composed of two side plates which straddle the casing 15 and engage the opposite ends of pin 21, the upper ends of the side plates being connected through a part 38 whereby the lever may be manipulated. When the cam lever is swung inwardly into ineffective position, the pin 21 may move toward the rear of the slots 37 to allow the roller 22 to fall away as the wick passes without actuating the brake member 25.

Referring now to the form of the invention illustrated in Figs. 3 and 4, 40 is an angle lever which carries a roller 41 at its upper end and that normally repose with- 40 in the upper end of the wick space 4 in the path of the wick 5. The opposite end of the lever is pivoted at 43 to the upper end of a brake member 44 and the lower end of the brake member is connected through 45 a link 45 with the corresponding end of a bar 46. The angle of the lever 40 is pivotally connected to the upper end of this bar. The lower branch of the angle lever 40, and the parts 44, 45, and 46 constitute 50 a parallelogram. The pins 47, which connect the ends of the bar 46 to the angle lever 40 and link 45, are restricted normally to a vertical course of movement so that the brake member 44 is retained at all 55 times in parallelism with the wick 5 by the ends of the lower pin being confined within vertical grooves 48 that are formed in the sides of the casing 15, and the ends of the upper pin being retained for movement 60 within the vertical branches of L-shaped slots 49 of the casing.

In operation, when the spindle 6 is rotated in a direction to elevate the wick, the upper end of the wick will engage the roller 41, displacing it inwardly and rock-

ing the angle lever 40 in a direction to throw the brake member 44 into engagement with the wick, or more properly, with the protecting strip 50 thereof. The wick will now continue to rise, carrying all parts of the stop mechanism with it until the pins 47 engage and are stopped by the upper ends of the grooves and slots 49. This will result in locking the wick against further upward movement after it has attained an elevation representing the maximum height of the wick.

To remove the wick from the burner in the present form of the invention, a cam lever 51, similar to the equivalent part 35 of the former embodiment may be swung on its pivot 52 away from the upper pin 47, allowing the pin to fall back into the horizontal branch of the L-shaped slot 49 when the roller 41 is engaged and moved by the wick, thereby to render the stop mechanism inoperative.

Thus it will be seen that my invention provides means for automatically stopping the wick at a predetermined elevation, which mechanism is positive of operation and requires no adjustment or attention of any kind, the same being self-adjusting to compensate for the variable length of the wick due to its being cleaned from time to time.

For the purposes of claims, the term "wick" may be regarded as inclusive or exclusive of the protecting strips 30 and 50.

Having thus described my invention, what I claim is:

1. In a burner of the character set forth involving a wick guide and means for raising the wick, a brake member for engagement with the wick, a member arranged to be engaged and moved by the wick when the latter is elevated, and operative connections between said members whereby the former is actuated by the latter.

2. In a burner of the character set forth involving a wick guide and means for raising the wick, a brake member for engagement with the wick, a member arranged to be engaged and moved by the wick when the latter is elevated, and operative connections between said members whereby the former is actuated by the latter, the brake member being capable of a limited movement bodily with the wick.

3. In a burner of the character set forth involving a wick guide and means for raising the wick, a brake member for engagement with the wick, a member arranged to be engaged and moved by the wick when the latter is elevated, operative connections between said members whereby the former is actuated by the latter, the brake member being capable of a limited movement bodily with the wick, and an adjustable stop for limiting the movement of the brake member.

4. In a burner of the character set forth involving a wick guide and means for raising the wick, a brake member for engagement with the wick and supported by the burner structure for limited movement in a plane parallel to the wick, a member arranged to be engaged and moved by the wick when the latter is elevated, and operative connections between the members whereby the former is actuated by the latter.

5. In a burner of the character set forth involving a wick guide and means for raising the wick, a brake member for engagement with the wick, means for sustaining the brake member substantially in parallel relation to the wick and permitting a limited bodily movement of the brake member with the wick, and means moved by the wick when the wick is elevated for engaging the brake member with the wick.

6. In a burner of the character set forth involving a wick guide and means for raising the wick, a bar supported by the burner structure for movement in a plane parallel to that of the wick, a brake member for engagement with the wick, connections between the brake member and bar, a member arranged to be engaged and swung laterally by the wick when the wick is elevated, and operative connections between the last mentioned member and the brake member, as and for the purpose specified.

7. In a burner of the character set forth involving a wick guide and means for raising the wick, a bar supported by the burner structure for movement in a plane substantially parallel to the plane of the wick, a brake member for engagement with the wick, links connecting the brake member and bar, and means arranged to be engaged and moved by the wick when the latter is elevated for moving the brake member into engagement with the wick, the assembly comprising the brake member, bar, and links being bodily movable with the wick, and an adjustable stop for limiting the movement of said assembly.

8. In a burner of the character set forth involving a wick guide and means for raising the wick, a bar supported by the burner structure for movement in a plane substantially parallel to the plane of the wick, a brake member for engagement with the wick, links having substantially correspondingly spaced points pivotally connected to equally spaced points of the brake member and bar, means arranged to be engaged and moved by the wick when the latter is elevated for moving the brake member into engagement with the wick, the assembly comprising the brake member, bar, and links being bodily movable with the wick, and a stop for limiting the movement of said assembly.

9. In a burner of the character set forth

involving a wick guide and means for raising the wick, a bar supported by the burner structure for movement in a plane parallel to that of the wick, a brake member for engagement with the wick, and elements having correspondingly spaced points pivotally connected to equally spaced points of the brake member and bar, one of said elements being arranged to be swung laterally by the wick when the wick is elevated thereby to move the brake member into engagement with the wick, the assembly comprising the brake member, bar, and elements being capable of a limited movement bodily with the wick.

10. In a burner of the character set forth involving inner and outer wick tubes between which a cylindrical wick is adapted to be guided, means for raising and lowering the wick, a casing within the inner wick tube the interior whereof communicates through a slot in the inner wick tube with the wick space, a brake member adapted to engage the wick through said slot, a bar within the casing, elements having correspondingly spaced points pivotally connected to equally spaced points of the brake member and bar, the pivotal connection between the bar and said elements involving pins, and the side walls of the casing having grooves wherein the pins are confined to a limited movement in a plane parallel to that of the wick, one of the aforesaid elements having an extension, and a roller carried by said extension in a position to be engaged and moved by the wick when the latter is elevated, thereby to swing the brake member into engagement with the wick.

11. In a burner of the character set forth involving inner and outer wick tubes between which a cylindrical wick is adapted to be guided, and means for raising and lowering the wick, a casing extending inwardly from the inner wick tube, the interior whereof communicates with the wick space through a slot in the inner wick tube, a brake member arranged to engage the wick through said slot, a bar within the casing, links having correspondingly spaced points pivotally connected to equally spaced points of the brake member and bar, anti-friction devices through which the assembly comprising the links, bar, and brake member bear upon the inner wall of the casing, said wall being parallel to the wick tubes, a lever pivotally supported within each casing and having a roller at its upper end which is adapted to be engaged by the upper end of the wick when the latter is elevated thereby to swing the lever on its pivot, the opposite end of the lever having an anti-friction bearing engaging the brake member, and a stop for limiting the upward movement of the assembly comprising the brake member, bar, and links.

12. In a burner of the character set forth, involving a wick guide and means for raising the wick, wick stop mechanism comprising a brake member for engagement with the wick, a member arranged to be engaged and moved by the wick when the latter is elevated, operative connections between said members whereby the former is actuated by the latter, and means for rendering said mechanism inoperative so that the wick may be removed from the burner.

13. In a burner of the character set forth involving a wick guide and means for raising the wick, a brake member for engagement with the wick, an actuator arranged to be engaged and moved by the wick and having operative connection with the brake member, the actuator when so moved and restricted to a given path of movement serving to present the brake member to the wick, and shiftable means which when in normal position restricts the actuator to said given path of movement, said means when shifted from normal position permitting the actuator to move without presenting the brake member to the wick.

14. In a burner of the character set forth involving a wick and wick raising means, wick stop mechanism operating independently of the wick raising means and which is normally inoperative, and means arranged to be engaged by the wick when the latter is elevated for rendering the stop mechanism operative.

15. In a burner of the character set forth involving a wick and wick raising means, wick stop mechanism operating independently of the wick raising means and normally reposing in inoperative position, and means arranged to be engaged by the wick when the latter is elevated for moving the stop mechanism to operative position.

16. In a burner of the character set forth involving a wick and wick raising means, wick stop mechanism operating independently of the wick raising means and which is normally inoperative, means arranged to

be engaged by the wick when the latter is elevated for rendering the stop mechanism operative, and means for throwing the stop mechanism out of commission so that the wick may be removed from the burner.

17. In a burner of the character set forth involving a wick and wick raising means, wick stop mechanism arranged to engage the wick and arrest its upward movement, said mechanism being normally inoperative, and an element arranged to be engaged by the wick when the latter is elevated for rendering the stop mechanism operative, said element being shiftable out of the path of the wick whereby the stop mechanism may be left inoperative so that the wick may be removed from the burner.

18. In a burner of the character set forth, in combination with the wick, mechanism involving both a stop arranged to engage the wick thereby to arrest its upward movement and an element adapted to be engaged and moved by the wick for rendering the stop effective.

19. In a burner of the character set forth, the combination with the wick, of wick stop mechanism involving an element arranged to be engaged and moved by the burned portion of the wick, and a member arranged to be moved by said element into contact with another portion of the wick thereby to arrest upward movement of the wick.

20. In a burner of the character set forth, in combination with the wick, wick stop mechanism involving parts respectively engaged by the wick to set the mechanism in operation, and engaging the wick to arrest the latter's upward movement.

21. In a burner of the character set forth, in combination with the wick, normally inoperative wick stop mechanism rendered effective by the movement of the wick and engaging the wick to arrest the latter's upward movement.

In testimony whereof, I hereunto affix my signature.

LEE S. CHADWICK.
